(57) **CLAIM**

I claim the ornamental design for a wolf figurine, as shown and described.

DESCRIPTION

FIG. 1 is a right-front view of a wolf figurine showing my new design;

FIG. 2 is a left-front view thereof;

FIG. 3 is a right-back view thereof;

FIG. 4 is a left-back view thereof;

FIG. 5 is a front view thereof;

FIG. 6 is a back thereof;

FIG. 7 is a left-side view thereof;

FIG. 8 is a right-side view thereof;

FIG. 9 is a top plan view thereof;

FIG. 10 is detail view thereof;

FIG. 11 is left-side detail view thereof; and,

FIG. 12 is right-side detail view thereof, showing the wolf figurine.

The bottom of the wolf figurine is an unadorned square, and no claim is made to the bottom.
